UNITED STATES PATENT OFFICE.

JULIUS J. BRELL, OF NEW YORK, N. Y., ASSIGNOR TO SIGMUND BASCH, OF NEW YORK, N. Y.

BUTTON PLACING AND RELEASING ATTACHMENT FOR SEWING-MACHINES.

1,193,504.

Specification of Letters Patent.

Patented Aug. 8, 1916.

Application filed May 5, 1914. Serial No. 836,401.

To all whom it may concern:

Be it known that I, JULIUS J. BRELL, a citizen of the United States, residing at the city, county, and State of New York, and whose post-office address is 530 West One Hundred and Fifty-ninth street, in said city, have invented a new and useful Improvement in Button Placing and Releasing Attachments for Sewing-Machines, of which the following is a specification.

The object of this invention is to provide a device of this class, wherein a button is received prior to being stitched to a fabric and then the button is so placed with regard to the sewing mechanism of the machine that the needle of the machine may pass through the various holes of the button while the same is being sewn to the fabric. This object is accomplished by my invention, one embodiment of which is hereinafter set forth.

For a more particular description of my invention, reference is to be had to the accompanying drawings, forming a part hereof, in which—

Figure 1 is a plan view of a structure provided with my improvement; Fig. 2 is a plan view of a portion of the mechanism for causing correct registration between the holes of the button and the needle of the machine; Figs. 3 and 4 are side and end views of a portion of the mechanism shown in Fig. 2; Fig. 5 is a side elevation of the structure shown in Fig. 1; Fig. 6 is a front view of my improved device looking toward the rear. This view is taken at right angles to the views shown in Figs. 1 and 5. Fig. 6 shows a detail of construction. Fig. 7 is a side elevation of the button clamping and holding mechanism; Fig. 8 is a front elevation of the clamping mechanism; Fig. 9 is a sectional view taken on the line 9—9 of Fig. 8, looking in the direction of the arrows; Fig. 10 is a side elevation of the button clamping and releasing mechanism; and Fig. 11 shows a cam plate and stop.

Throughout the various views of the drawings, similar reference characters designate similar parts.

My improved placing device 10 may be applied to any suitable sewing machine 11 and the manner of its application will depend upon the structure of the sewing machine. In the embodiment shown, the machine 11 is provided with a suitable bed plate

12, which carries the mechanism of the sewing machine and the placing machine. In any event, the needle 13 of the sewing machine is provided with a suitable thread 14 for sewing the button 1 in place and this needle is mounted so as to reciprocate in the arm 15 in the usual way. It is not necessary to describe the details incidental to the mounting and driving of the needle, as they form no part of my invention.

A second arm 16 carries a slidably mounted and vertically disposed bar 17 to which the clamping mechanism is attached. This bar 17 is normally pressed downwardly by means of a suitable spring 18 or any other suitable device. This bar 17 has a projecting pin 19 which is adapted to engage a corresponding projection 20, so that when the needle mechanism is raised, the bar 17 may also be raised against the spring 18 and so are the parts carried thereby.

The lower end of the bar 17 is bent forwardly at right angles to form a foot 21 to which is secured by means of a suitable screw 22 a plate 23, on which the jaws 2 and 3 of the clamp are pivotally mounted, the jaw 2 being pivoted at 24 and the jaw 3 at 25. These two clamps are normally pressed together by means of a suitable spring 26, as indicated by dotted lines in Fig. 9. Below the jaws 2 and 3 and slidably mounted on suitable cap screws 27 is the cam plate 6. This cam plate 6 is supported directly below the jaws 2 and 3 by means of these screws 27 and at one edge this plate 6 is suitably recessed at 7 for a purpose that will appear below.

The screws 27 ride in divergent slots 28, which are nearest together at the rear and separated widest at the front, as appears in Fig. 11. From this it appears that as this plate slides a slight distance forward or back, the jaws 2 and 3 are either brought together or separated, they are brought together on the forward movement and separated at the rearward movement, as is obvious.

The stop 4 is carried by the plate 23 by means of a suitable cap screw 29 that rides in a corresponding slot 30 in the plate 23, so that this stop 4 may be adjusted for various sizes of buttons.

The spring 26 which holds the jaws 2 and 3 in proper relation, is preferably mounted at its rear on a suitable screw 31, although

it may be mounted in any other suitable way, if desired.

It will be noted that the jaws 2 and 3 and the stop 4 are bent downwardly and forwardly near their forward ends, so as to carry the button 1 well below the level of the plate 23. The extreme front ends of these parts 2, 3 and 4 are made horizontal, the jaws 2 and 3 being provided with horizontal grooves 32 to carry the button 1.

From the foregoing, it is apparent that the jaws 2 and 3 may be separated by shoving back the plate 6 and brought together by the action of the spring 26, when pressure is removed from the cam plate 6. When, however, it is desired to make the machine automatic in this respect, this can be accomplished by providing a bracket 33, which is secured to the head 16, as shown in Figs. 8, 9 and 10. The preferable way is to fix this bracket 33 by means of suitable screws 34, but any other means may be adopted, as desired. At the outer and forward end of the bracket 33 is a pivot 35 which carries a suitable cam 36 which has a bevel cam edge 8, which is adapted to enter the recess 7 of the plate 6. A suitable leaf spring 37 is secured to the bracket 33 and normally presses this pivoted cam 36 against a screw 38, set in the jaw 3. The construction is such that when the bar 17 is raised, as by the action of the projection 20 on the projection 19, or otherwise, then the plate 6, acting through its recess 7, is forced inwardly by the bevel cam 8, which is so pivoted that pressure against the bevel cannot swing this pivoted cam. The forcing of the plate 6 toward the rear swings the jaws 2 and 3 apart and thereby separates the cam 8 from the recess 7, the screw 38 being properly adjusted for this purpose. This separation of the jaws takes place in the first quarter of their elevation and thereafter they are free to return to their normal condition undisturbed by the cam 36 which is swung outwardly against the pressure of the spring 37. When the jaws separate, the button is left sewn to the cloth, and then the jaws are restored to their normal position and a new button is shoved against the stop 4 between the jaws 2 and 3. The mechanism for properly placing this button with regard to the needle 13 will now be described. This needle 13, as above stated, sews three stitches in each hole, or twelve stitches in all, in the embodiment of the invention herein shown and described. The button remains stationary, while the needle is shifted after each return movement from the button hole last entered. The button is rotated between the parts 2, 3 and 4 by means of a spring pressed finger 5 which is pivoted at 39 in a reciprocating link 40. This finger 5 has at its upper end a suitable notch which receives a coiled spring 41 secured to a projection 42 on the

link 40. This spring 41 is so made and disposed that it tends to throw upwardly the lower end of the finger 5. The bed 12 of the machine has several parts fixed therein, in any suitable manner, one of which is a plate 43 and an arm 44 fixed to the plate 43 by means of a suitable cap screw 45. At the forward end of this arm 44 are mounted two parts which are held by a suitable screw 46. The upper one of these parts is a suitable spring 47 which rests on the link 40 and prevents the same from rising, except against the tension of this spring 47. The other part is shown in detail in Fig. 6a and comprises a plate 48, which is pivoted on the screw 46 so as to be capable of adjustment thereon and this plate 48 has two parts, one of which, 49, is horizontal and runs under the link 40 and the other, 50, is vertically disposed and rests against one side of this link 40. From this, it is apparent that the link 40 has guides on three sides, namely a spring 47 on top, the projection 49 below and the upright 50 on one side. This leaves one side which is not controlled by a guide.

The rear end of the link 40 is connected by a suitable bolt or screw 51 to the angle metal pivot 52 which is pivoted at 53 to a collar 54, which is mounted on a suitable screw 55, so as to turn thereon. A projecting ear 56 carries a coiled spring 57, the other end of which is attached to a post 58 which rises from a slide 59. The slide 59 is normally retracted by a coiled spring 60, which is secured to the post 58 at its forward end and to a post 61 at its rear end. This post 61 rises from the plate 43 and is fixed therein. The rear end of the slide 59 is provided with a large head 62 and a transverse slot 63 in which runs a pin 64 on a lever 65, which is fulcrumed at 66 to a screw projecting from the plate 43. The other end of this lever 65 has a suitable slot 67, in which is secured a pivot 68 which is adjustably mounted thereon and provided with a suitable cord or cable 69 that runs to a foot pedal, not shown. By pressing on this foot pedal, the lever 65 has its pin 64 thrown to the front of the machine against the tension of the spring 60 and thereby forces the bar 40 to the front. While the jaws 2 and 3 are raised, a button 1 is inserted between them as will appear below. As the spring 60 causes the slide 59 to return toward the rear, when the pressure on the treadle is released, the spring finger 5 is drawn to the rear, and while so being drawn, it wipes the button, enters a hole therein, if not already in a hole, and rotates the button on its axis until the button is turned to such an extent that it cannot be easily turned any more by the withdrawal of the finger 5 and then the finger leaves the button hole and gets clear of the sewing mechanism. The action of

this finger is such that the button is turned so as to cause a perfect registration and the needle goes through the button hole set for it. This foot pedal also raises the projection 20 of the sewing machine and through it the projection 19, the bar 17 and plate 23. The front end of the bar 40 is raised along with the plate 23 and bar 17 and the parts connected therewith by means of a wire 10 secured to a suitable screw 71 mounted on the plate 23. The pivot 53 lets this bar 40 be raised against the tension of the spring 47. The screw 71 may, if desired, pass through a suitable slot 72 in a pivoted arm 73 which is 15 pivoted at 74 in the plate 23. This arm 73 may press against the screw 29 and so prevent the same from moving too far forward in the slot 30 and the adjustment, because of the slot 72, can be made very nice, so that the 20 stop 4 will always be placed in right relation for the button placed between the jaws 2 and 3, although any of several sized buttons may be used in the machine.

Assuming the jaws ready to receive the 25 button 1, the operation is as follows: The jaws 2 and 3 are spring-pressed and pivoted and when the button is placed in the recesses 32 between them, it is pressed inwardly to the stop 4 and there remains. The button 1 30 is inserted while a treadle is pressed and the clamping jaws 2 and 3 are elevated. As the button is put in place, as above described, it presses against the spring finger 5 and forces the same inwardly a slight distance. As the 35 clamp is lowered, the spring finger is also lowered to correspond for a certain distance, but not the entire movement of the clamp, and when the finger and clamp begin to separate, the spring finger begins to assume a 40 vertical position and in so assuming, turns the button on its axis until the same is in proper position for the sewing mechanism of the machine. This occurs when the clamp is about three-quarters lowered and thereafter 45 the button is in proper position. The further lowering of the clamp separates the finger from the button and the finger thereafter remains in its normal position and will not be swung on its vertical pivot until the next 50 cycle of the machine, when the next button is inserted. The finger is pressed forward, as above described, by the treadle and when the treadle is released, the finger is drawn inwardly toward the rear of the machine and 55 while being so drawn, forces the button against the stop 4. The button is then sewn to the fabric in the usual manner, twelve stitches being employed, three through each of the four holes of the button, and there- 60 after the sewing machine automatically stops with the needle elevated. The treadle is again pressed and the clamp with the jaws 2 and 3 and the stop 4 is raised, as above described. As the clamp rises, one wall of the 65 recess 7 engages the cam 8 and the plate 6

is shifted rearwardly and thereby spreads the jaws 2 and 3 against the action of the spring enough to release a button. This separation occurs during the first quarter of the elevation of the jaws, and then the spring 70 of the jaws forces the cam edge 8 out of the recess 7, and thereby permits the plate 6 to come forward and close the jaws to normal, where they remain and thereafter, the cam 8 is not operative during the remaining three- 75 quarters elevation and the next lowering of the clamp. The jaws 2 and 3 are then in their normal position, and ready to receive a button, when the above cycle is repeated. The feed of the cloth in the sewing machine 80 takes care of the spacing of the buttons on the fabric.

While I have shown and described one embodiment of my invention, it is obvious that it is not restricted thereto, but is broad 85 enough to cover all structures that come within the scope of the annexed claims.

I claim—

1. In a machine of the class described, in combination, stitch forming mechanism including a needle, a button holder provided with jaws and means for causing said jaws to engage or release a button and hold the same over the substance to which it is to be attached, means for shifting the button about 90 its axis while held between the button holding jaws so that the button holes will register with said needle.

2. In a machine of the character described, in combination, stitch forming mechanism 100 including a needle, means for holding a button over the substance to which it is to be attached, means for causing the button to turn in the button holding means until its holes register with said needle which is to sew it in 105 place, and means for releasing the button after the same has been sewn.

3. In a machine of the class described, in combination, stitch forming mechanism including a needle, means for holding a button, means for shifting the button while held in the button holding means until its holes register with said needle which will be used for sewing the button in place and elevating means for raising the button holding mech- 110 115 anism, and simultaneously causing it to release the button after it has been sewn in place.

4. In a machine of the class described, jaws for holding a button, means for raising 120 said jaws, actuating means for drawing together or separating said jaws and mechanism for driving said actuating means so that the jaws will be separated during the first part of their elevating movement, then be 125 brought together, and not thereafter separated until the next raising of these jaws.

5. In a machine of the class described, in combination, stitch forming mechanism including a needle, jaws for holding a button, 130

- means for raising said jaws, actuating means for drawing together or separating said jaws, mechanism for driving said actuating means so that the jaws will be separated during the first part of their elevating movement, then be brought together, and not thereafter separated until the next raising of these jaws, and means for placing a button in said jaws so that its holes will register with said needle. 65
6. In a machine of the class described, jaws for holding a button, means for raising said jaws, actuating means for drawing together or separating said jaws, mechanism for driving said actuating means so that the jaws will be separated during the first part of their elevating movement, then be brought together, and not thereafter separated until the next raising of these jaws, 70 a finger adapted to rotate a button in said jaws, means for supporting said finger and means for actuating said finger supporting means. 75
7. In a machine of the class described, a bar and means for elevating or lowering the same, a foot secured to said bar, a plate secured to said foot and button holding jaws pivoted to said plate and means for rotating a button while held in said jaws. 80
8. In a machine of the class described, a bar and means for elevating or lowering the same, a foot secured to said bar, a plate secured to said foot, button holding jaws pivoted to said plate, and a spring pressing said jaws so as to clamp said jaws against a button and means for rotating a button while held in said jaws. 85
9. In a machine of the class described, a bar and means for elevating or lowering the same, a foot secured to said bar, a plate secured to said foot, button holding jaws pivoted to said plate, a cam plate and connections between said plate and jaws and means for turning a button while held by said jaws. 90
10. In a machine of the class described, a bar and means for elevating or lowering the same, a foot secured to said bar, a plate secured to said foot, button holding jaws pivoted to said plate, a spring pressing said jaws so as to clamp said jaws against a button, a cam plate and connections between said plate and jaws and means for turning a button while held by said jaws. 95
11. In a machine of the class described, a bar and means for elevating or lowering the same, a foot secured to said bar, a plate secured to said foot, button holding jaws pivoted to said plate, a spring pressing said jaws so as to clamp said jaws against a button, a cam plate, connections between said plate and jaws, mechanism for opening said jaws against the action of said spring and means for turning a button while held by said jaws. 100
12. In a machine of the class described, a bar and means for elevating or lowering the same, a foot secured to said bar, a plate secured to said foot, button holding jaws pivoted to said plate, a spring pressing said jaws so as to clamp said jaws against a button, a cam plate, connections between said plate and jaws, and mechanism for shifting a button held by said jaws so that registration with a needle is obtained. 105
13. In a machine of the class described, a bar and means for elevating or lowering the same, a foot secured to said bar, a plate secured to said foot, button holding jaws pivoted to said plate, a spring pressing said jaws so as to clamp said jaws against a button, a cam plate, connections between said plate and jaws, mechanism for opening said jaws against the action of said spring, and mechanism for shifting a button held by said jaws so that registration with a needle is obtained. 110
14. In a machine of the class described, a link, a vertical finger pivoted on the end of said link, adapted to move rearwardly at its lower end against the tension of a spring, the spring engaging the upper end of said finger and extending between the upper end of said finger and the link, and a slide pivotally connected to the end of the link. 115
15. In a machine of the class described, a link, a slot in the end of said link, a vertical finger pivoted in said slot, so that its lower end may swing rearwardly against the tension of a spring, the spring extending between the upper end of the finger and the link and above the pivot for said finger, a spring bearing on the top of said link, a guide below said link and on one side of said link, said link being pivoted at one of its ends to a slide, and means for reciprocating said slide. 120
16. In a machine of the class described, a link, a vertical finger pivoted to one end of said link, a spring connecting the upper end of said finger and the link, a spring bearing on the upper side of said link, a guide beneath said link having an upright stud acting as a guide for one side of said link, said link being pivoted at one of its ends to a slide, mechanism connected to one end of said slide for moving the same forward and a spring for retracting said slide. 125
